UNITED STATES PATENT OFFICE.

GEORGE J. ZEIS, OF BUFFALO, NEW YORK.

DESIGN FOR AN ORNAMENT FOR RADIATOR CAPS.

Application filed October 2, 1924. Serial No. 10,953. Term of patent 3½ years.

To all whom it may concern:

Be it known that I, GEORGE J. ZEIS, a citizen of the United States, residing at Buffalo, in the county of Erie and State of New York, have invented a new, original, and ornamental Design for an Ornament for Radiator Caps, of which the following is a specification, reference being had to the accompanying drawing, forming part thereof.

The drawing is a perspective view of an ornament for radiator caps, showing my new design.

I claim:

The ornamental design for an ornament for radiator caps, substantially as shown.

GEORGE J. ZEIS.
